UNITED STATES PATENT OFFICE.

ARTHUR A. KRAEUTER, OF SOUTH ORANGE, NEW JERSEY, ASSIGNOR TO THE KROYDON COMPANY, OF NEWARK, NEW JERSEY, A CORPORATION OF NEW JERSEY.

GOLF CLUB.

Application filed July 15, 1925. Serial No. 43,665.

This invention relates to improvements in golf clubs and more particularly to a method and means of locking the sole plate on and to the bottom face of wooden golf clubs or golf clubs having wooden heads such as drivers, brassies, spoons and the like.

The principal object of this invention is the provision of a construction in which the sole plate is securely locked and held in position and in which all shocks and strains of any kind to which it and the club head are subjected through it are taken up by the locking means in such a way as not to interfere with the attaching means of the sole plate to the club head or in such a way as to detrimentally affect the head of the club itself.

A further object is the provision in a construction of this kind of a locking key or ring which is interposed between the sole plate and the club head and has portions projecting into and fitting into both the sole plate and the club head whereby the strains and stresses are taken up by the locking key or ring and not by the attaching means or the club head itself. In other words, the locking key or ring relieves the attaching means and also the sides of the recess in the bottom of the head of the club from any shocks and strains arising from impact with the sole plate.

To the accomplishment of the foregoing and such other objects as may hereinafter appear this invention consists in the construction, combination and arrangement of parts hereinafter described and then sought to be defined in the accompanying drawings forming a part hereof and which show, merely for the purpose of illustrative disclosure, a preferred embodiment of this invention, it being expressly understood that various changes may be made in practice within the scope of the claims without digressing from my inventive idea.

In the drawings—

Figure 1 is a perspective view of the head of a golf club, parts being shown broken away and in vertical section substantially on line 1—1 of Figure 2.

Figure 2 is a bottom plan view of a golf club head construction embodying my invention.

Figure 3 is a bottom plan view of a golf

head construction before the sole plate and key are assembled thereon.

Figure 4 is a bottom plan view of the sole plate itself.

Figure 5 is a bottom plan view of the key itself.

Referring now to the drawing, the numeral 1 designates a wooden club head of any one of the ordinary forms of wooden golf clubs at present in use. These club heads are formed of standard shapes and sizes, all of which form no part of this present invention. It is provided with the face 2 which is inclined according to the type of the club and also has a rounded rear portion 3 and the bottom face or surface 4. In the form shown, this bottom face or surface is provided with a groove or recess 5 extending entirely therethrough from the front or face to the rear or back of the club and this recess may be of any desired shape. While the illustration shows that the recess is of a general tapered formation narrowing toward the rear face of the club, this is not essential being merely a matter of convenience for the purposes hereinafter set forth.

The sides 6 of this groove or recess are in the form of straight shoulders and are adapted to receive the sole plate 7 which corresponds in shape to the shape of the recess, having the sides 8 which are adapted to fit the sides 6 of the recess, having the rear end 9 rounded to conform to the curve and shape of the rear end of the club and having the front end 10 similarly shaped to correspond to the lower part of the front face of the club, and the front and bottom portion thereof as illustrated, as is well understood. This plate 7 is preferably of metal or it may be made of other suitable material. It is provided with a plurality of apertures 11 suitably placed and preferably countersunk as illustrated to receive the screws or other securing means 11' which pass therethrough and into the club head to hold the sole plate in position on the club head. The club head itself on the inner face or recess of the groove 5 is formed with a groove or recess or keyway 12 and the inner face of the sole plate 7 is formed with a groove or recess or keyway 13 of similar or complementary shape to the groove or recess or keyway 12. In the illustration these key-

ways 12 and 13 are shown to be of circular shape, and this is the preferred form, though it is to be understood that they may be of other forms as long as they provide 5 a keyway of sufficient length and thickness for the purposes hereinafter set forth. These keyways 12 and 13 are adapted to receive a key 14 which in the form shown is ring shaped and fits into the keyway 12 10 and also into the keyway 13 securely locking and holding the sole plate in position horizontally with reference to the club head. The keyways 12 and 13 are of sufficient depth and the key 14 is of sufficient thickness to receive and withstand the shocks and strains which are transmitted through the sole plate in the use of the club and prevent these shocks and strains falling upon the screws or other securing means or 15 upon the sides 6 of the groove or recess 20 5. It is the main purpose of this invention to prevent these latter actions and to take up any shock or strain which develops in use through blows upon the sole plate by 25 means of the locking key or ring 14, and to relieve the securing means 11 and the sides 6 of the groove or recess 5 of such shocks and strains in the use of the club and upon impact with the ball or ground. 30 In the form shown this locking key or ring is made of Babbitt or other suitable metal and is formed in place after the sole plate is attached, and to that end the sole plate is provided with the aperture 15 and 35 the head of the club is provided with the leads 16 in the form of grooves or passageways connecting with the groove or keyway 12. The molten Babbitt metal is poured in through the aperture 15 and fills the keyways 12 and 13 and forms the circular key or ring 14 having an integral central projection 17 filling the hole 15 through the sole plate. Of course, it is to be understood that 40 this key ring may be formed of other material and in other ways and this is described as one method of making the same and one 45 construction.

It is an essential requirement of this construction that the key which is interposed 50 between the club head and the sole plate and fits in both the club head and the sole plate, shall be of sufficient dimension in thickness, depth and length so as to afford a secure and ample bearing to take up all the shocks and strains due to impact when the club is 55 in use and relieve the sides of the recess and also the securing means of such shocks and strains. By providing this key in circular form I am able to obtain the greatest lineal dimension within the area or compass of the sole plate.

What I claim is:—

1. In combination a golf club head having a recess formed in its under surface, a sole 60 plate positioned within said recess, securing

means for attaching said sole plate to said club head and means interposed between said sole plate and said club head for taking up all shocks and strains due to impact with the sole plate and relieving the sides of said recess and said securing means of said shocks and strains. 70

2. The combination of a club head having a recess formed in the bottom surface thereof, a sole plate positioned in said recess, securing means for attaching said sole plate to said club head, a key member interposed between said sole plate and said club head, said sole plate and said club head being each provided with keyways to receive the parts of 80 said key member for the purpose of taking up all shocks and strains due to impact with the sole plate and relieving the sides of said recess and said securing means of said shocks and strains. 85

3. The combination of a club head having a recess formed in the bottom surface thereof, a sole plate positioned in said recess, securing means for attaching said sole plate to said club head, said sole plate being 90 formed with a keyway on its inner surface, said club head being formed with a similar or complementary keyway in its under surface, and a key member adapted to fit in said keyways and to take up all shocks and 95 strains due to impact with the sole plate and relieve the sides of said recess and said securing means of said shocks and strains. 100

4. The combination of a club head having a recess formed in the bottom surface thereof, a sole plate positioned in said recess, securing means for attaching said sole plate to said club head, said sole plate having a circular keyway formed on the inner surface thereof, said club head having a corresponding and complementary keyway formed on the under surface thereof and a circular key member positioned in said keyways to take up all shocks and strains due to impact with the sole plate and relieve the 110 sides of said recess and said securing means of said shocks and strains. 105

5. The combination of a club head having a groove or keyway formed in the bottom thereof, a sole plate for the bottom of said club head having a groove or keyway formed therein, a separate element for engaging said groove or keyway in the club head and the groove or keyway in the sole plate to lock the parts together and take up all shocks and strains due to impact in use. 115

6. The combination of a club head having a groove or keyway formed in the bottom thereof, a sole plate for the bottom of said club head having a groove or keyway formed therein, and a key member cast in said grooves or keyways for locking the parts together and taking up all shocks and strains due to impact in use. 120

7. The combination of a club head having 130

a groove or keyway formed in the bottom thereof, said groove or keyway being circular in shape, a sole plate for the bottom of said club head having a complementary 5 groove or keyway formed therein, said club head having an additional groove extending across the circular groove to form leads and said sole plate having an aperture communicating with said leads, a key element 10 cast in position by pouring molten metal

through said aperture into said leads and said grooves or keyways whereby the parts are locked together and all shocks and strains due to impact in use are taken up by the key element.

In testimony that I claim the foregoing, I have hereunto set my hand this 11 day of June, 1925.

ARTHUR A. KRAEUTER.
